Design U.S. Appl. No. 29/707,842, Jae Chung et al., filed Oct. 1, 2019.

Primary Examiner — Stacia A Cadmus

(74) Attorney, Agent, or Firm — Plumsea Law Group, LLC

(57) **CLAIM**

The ornamental design for a wheel, as shown and described.

DESCRIPTION

FIG. 1 is a front perspective view of a wheel showing my new design.

FIG. 2 is a rear perspective view thereof.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof; and,

FIG. 8 is a bottom plan view thereof.

The broken line showing of portions of the wheel form no part of the claimed design.

1 Claim, 6 Drawing Sheets(56)
